UNITED STATES PATENT OFFICE

2,360,350

COSMETIC OR LIKE HOLDER

Hugo Montague Kirk-Schneider, New York, N. Y.

Application October 10, 1942, Serial No. 461,519

3 Claims. (Cl. 206—56)

This invention relates to improvements in cosmetic articles and more particularly to lipstick holders.

It is an object of the present invention to provide a novel simple, efficient and practical non-metallic lipstick holder and preferably made of plastic material.

It is a further object of the present invention to provide a lipstick holder characterized by its simplicity of manufacture and assembly.

Another object of the present invention is to provide a lipstick holder which is aesthetic in its appearance and adapted to contain different colors or combinations.

It is another object to provide a lipstick container which is non-operable in its closed position.

Yet another object of the present invention is to provide a lipstick container or holder having a closure which is clampingly held against the base of the holder to prevent its accidental removal therefrom.

These and other objects and advantageous features are accomplished by the simple, novel and practical construction, combination and arrangement of parts hereinafter disclosed and illustrated in the accompanying drawing, constituting an essential part of the disclosure, and in which:

Fig. 1 is an elevational view of a lipstick holder made in accordance with the invention and shown in closed inoperative position;

Fig. 2 is a vertical sectional view taken through Fig. 1;

Fig. 3 is a detached view (parts in section) of the base of the device;

Fig. 4 is a top plan view of Fig. 3;

Fig. 5 is a cross-sectional view of the outer or handle sleeve of the device;

Fig. 6 is a plan view of Fig. 5;

Fig. 7 is an outside view of the spirally slotted sleeve;

Fig. 8 is a plan view of Fig. 7;

Fig. 9 is a vertical section taken through the straight-slotted sleeve;

Fig. 10 is a plan view of Fig. 9;

Fig. 11 is a cross-section taken through the lipstick carrier sleeve; and

Fig. 12 is a cross-sectional view taken through Fig. 11.

It is preferable to make all of the parts embodied in the lipstick holder of plastic composition of the same or a combination of suitable and pleasing types. Such materials may be cellulose acetate, catalin, polystyrene, methyl methacry-

late plastic, pyroxylin, other ethers and esters of cellulose or certain horn-like materials or synthetic resinous compounds, etc.

Referring now more particularly to the drawing, the lipstick holder generally indicated by the numeral 15 comprises the closure or cover 16, base 17, handle or operating sleeve 18, the sleeve 19 having the spiral slot 20, inner sleeve 21 having the vertical slot 22, and the lipstick carrier sleeve 23 having a transverse pin 24 projecting outwardly through opening 25 in carrier 23 as indicated at 26.

Housing 16 is provided with a preferably dome-shaped top 27. The bottom edge 28 of housing 16 is preferably provided with a plurality of inwardly directed bosses 28a which are adapted to clampingly grip the constriction 29 in base member 17. Base number 17 comprises the enlarged disc portion 30 to be gripped by the fingers of the user for turning the sliding mechanism hereinafter described. The constriction 29 is formed between portion 30 and the annulus 31, arcuate in cross-section, the bottom portion 28 of the closure sliding over this annulus when the same is positioned upon the base 17.

Base 17 has an annular groove or recess 32 in which is secured by cement or otherwise the lower edge 33 of inner sleeve 21.

The outside diameter of the spirally slotted sleeve 19 is such that it forms a tight friction fit with the inside wall 35 of the operating sleeve 18. It is understood that the spiral slot 20 may be formed on the inner wall of the operating sleeve 18, thus eliminating a part, namely, the sleeve 19.

Inner sleeve 21 having the slot 22, has a cut 36 extending from the slot 22 upwardly to the rim 37 to permit insertion of the lipstick carrier 23 in the inner sleeve 21 with the pin 26 projecting through the slot 22. Spirally slotted sleeve 19 has the spiral 20 terminating in an opening 38 at the top edge of sleeve 19 permitting the extension 26 of pin 24 to enter spiral slot 20.

After inner sleeve 21 has been secured to base 17 in the groove 32, and after lipstick carrier 23 has been inserted so as to engage the straight slot 22 and spiral slot 20, the top edge 37 of inner sleeve 21 is turned over outwardly as seen at 37a, thus holding the various parts in operative alignment and assembly.

Spiral sleeve 19 being frictionally secured to the inside 35 of operating sleeve 18, if the base 17 of the lipstick holder is held by fingers of one hand, while fingers of the other hand en-

gages the operative sleeve 18, relative turning of the base and sleeve will cause the pin extension 26 to ride upwardly in the straight slot 22 thus expelling the lipstick L for use. Reversing this operation will again return the lipstick into the holder by causing extension of pin 26 to ride downwardly in the slot 22 by virtue of the spiral 20.

Lipstick L is securely held in the carrier 23 by the pin 24, the latter thus serving two functions, namely, as a grip for the lipstick and as a guide pin operating in slots 20 and 22.

It is understood that although the invention has been described as being applicable to a lipstick, the same may be used in connection with any medicinal or marking device which in inoperative position is concealed within the holder and which may be projected for use.

From the foregoing it may be realized that, as one aspect of the invention, there is provided a plastic holder for lipstick or the like, comprising the base 17 having a peripheral groove or constriction 29, an annular portion 31 extending upwardly from constriction 29 and an annular recess 32 in base 17; the inner sleeve 21 being secured to the base in said recess, the inner sleeve 21 having a straight slot 22, the outer sleeve 18 disposed over the inner sleeve; a tubular member 19 having a spiral slot therein, member 19 fixedly engaging the inner wall of outer sleeve 18; a tubular lipstick carrier 23 operable within inner sleeve 21, carrier 23 having a transverse pin 24 therewithin and adapted for engagement with the bottom of the lipstick, pin 24 extending through straight slot 22 and engaging the spiral slot of member 19; outer sleeve 18 and base 17 being relatively rotatable, a cut 36 being provided in inner sleeve 21 extending from the top of straight slot 22 to the upper rim 37 thereof to facilitate reception of carrier 23 within the inner sleeve; upper rim 37 being turned outwardly or otherwise enlarged providing a stop retaining outer sleeve 18 between base 17 and rim 37; and a cap or housing 16 covering outer sleeve 18 and adapted to engage with base 17 over annular portion 31 of the base.

It will thus be seen that there has been provided by this invention a cosmetic or like holder in which the various objects hereinabove set forth, together with thoroughly practical advantages, are successfully achieved.

As changes may be made in the embodiment above set forth, it is to be understood that the matter hereinbefore set forth or shown in the accompanying drawing is to be interpreted as illustrative and not in a limiting sense.

Having thus described the invention, what is claimed as new and desired to be secured by Letters Patent, is:

1. A plastic holder for lipstick and the like, comprising a base, said base having a peripheral groove, an annular portion extending upwardly from said groove, said portion being arcuate in cross section, and an annular recess in said base, an inner sleeve secured to said base in said recess, said inner sleeve having a straight slot, a rotatable outer sleeve disposed over said inner

5 sleeve, a tubular member having a spiral slot therein, said member fixedly engaging the inner wall of said outer sleeve, a tubular lipstick carrier operable within said inner sleeve, said carrier having a transverse pin within said carrier and adapted for engagement with the bottom of the lipstick, said pin extending through said straight slot and engaging said spiral slot, said outer sleeve and said base being relatively rotatable, said inner sleeve having a cut extending from the top of said straight slot to the upper rim thereof to facilitate reception of said carrier within said inner sleeve, said upper rim being turned outwardly providing a stop retaining said outer sleeve between said base and said rim, and a cap covering said outer sleeve and in engagement with said base over said annular portion of said base and at said peripheral groove.

2. A holder for lipstick or the like, comprising a base, said base having a constriction, an annular portion extending upwardly from said constriction, said portion being arcuate in cross section, and an annular recess in said base, an inner sleeve secured to said base in said recess, said inner sleeve having a straight slot, an outer sleeve disposed over said inner sleeve and having a spiral groove therein, a tubular lipstick carrier operable within said inner sleeve, said carrier having a transverse pin within said carrier and adapted for engagement with the bottom of the lipstick, said pin extending through said straight slot and engaging said spiral groove, said outer sleeve and said base being relatively rotatable, said inner sleeve having a cut extending from the top of said straight slot to the upper rim thereof to facilitate reception of said carrier within said inner sleeve, said upper rim being turned outwardly providing a stop retaining said outer sleeve between said base and said rim, and a cap covering said outer sleeve and in engagement with said base over said annular portion and at said peripheral groove.

3. A holder for lipstick or the like, comprising a base, said base having a constriction, an annular portion extending upwardly from said constriction, and an annular recess in said base, an inner sleeve secured to said base in said recess, said inner sleeve having a straight slot, an outer sleeve disposed over said inner sleeve and having a spiral groove therein, a tubular lipstick carrier operable within said inner sleeve, said carrier having a transverse pin within said carrier and adapted for engagement with the bottom of the lipstick, said pin extending through said straight slot and engaging said spiral groove, said outer sleeve and said base being relatively rotatable, said inner sleeve having a cut extending from the top of said straight slot to the upper rim thereof to facilitate reception of said carrier within said inner sleeve, said upper rim being turned outwardly providing a stop retaining said outer sleeve between said base and said rim, and a cap covering said outer sleeve and in engagement with said base over said annular portion and at said peripheral groove.

H. MONTAGUE KIRK-SCHNEIDER.
